MARINE STEERING DEVICE

Walter Leland Jones, Webster Groves, Mo.

Application May 19, 1948, Serial No. 28,907

8 Claims. (Cl. 114—165)

1

This invention relates to marine steering devices, and more particularly to a portable steering apparatus for small craft.

Among the several objects of this invention may be noted the provision of a marine steering device which may be readily and conveniently mounted on small water craft of various types, sizes and contours; the provision of a device of the class described in which various elements may be expeditiously detached from a water craft without the use of hand tools; and the provision of a device of the class described which is not susceptible to damage by floating or underwater obstructions or debris, regardless of how these are encountered. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a top plan view of the device of the present invention attached to a canoe, with parts being broken away;

Fig. 2 is a side elevation of Fig. 1, illustrating several alternative positions of parts;

Fig. 3 is the rear view of the aft portion of the device, illustrating two alternative rudder positions;

Fig. 4 is a horizontal section on an enlarged scale taken substantially along the line 4—4 of Fig. 3;

Fig. 5 is an enlarged exploded perspective view of a control member pedal;

Fig. 6 is an enlarged vertical section taken substantially along line 6—6 of Fig. 1 but with the rudder in a reverse position;

Fig. 7 is an enlarged horizontal section taken substantially along line 7—7 of Fig. 2;

Fig. 8 is an enlarged vertical section taken substantially along line 8—8 of Fig. 1; and

Fig. 9 is a horizontal section on an enlarged scale taken substantially along the line 9—9 of Fig. 6.

Similar reference characters indicate corresponding parts throughout the several views of the drawings.

Referring to the drawings, a water craft (canoe, for example) is indicated generally at numeral 1. The rudder elements of the present invention are indicated generally by numeral 3. 55

A contour-fitting stern clamp or attachment 5 is removably affixed to the stern of the canoe 1 by means of a pintle or bolt 7. The stern attachment, bracket or clamp 5 comprises several 5 wooden laminae 9, two pliable sheets 11, and two side plates 13. The laminae 9 have their forward surfaces shaped to correspond approximately to the contours of the stern of the canoe 1. The sheets 11, which may be conveniently made of canvas, are originally cut to such dimensions as to extend beyond the forward edges of side plates 13. A hardenable plastic layer 15 is located between the sheets 11 and laminae 9. Side plates 13, sheets 11 and laminae 9 are firmly held together by means of several bolts 17. Farther rearward the plates 13 are clamped by bolts 4 to opposite sides of a spacer block 2. Bolt 7 is engageable in an aperture 21 in a protector strip 23 of the canoe 1 to couple the clamp 5 to the stern of the canoe 1. The two jaws of the clamp 5 have aligned apertures 25 and holes 27 at the outer ends of the apertures 25. The holes (shown more particularly in Fig. 7) are cut only in the side plates 13 while the apertures 25 are cut 25 through the laminae 9 as well as through the plastic layer 15 and sheets 11. An arm 29 having a circular boss 31 adapted to be journaled in each hole 27 is mounted on each side plate 13. Boss 31 is affixed to arm 29 by rivets 30. The 30 bosses 31 each carry an eccentrically bored aperture 32 adapted to receive the bolt 7. Each arm 29 also carries at one extremity a second aperture 33 adapted to receive a locking bolt 35 and nut 36. This bolt 35 may be inserted through any one of several locking apertures 37 in clamp 5. Rotation of the arms 29 through action of the eccentrics forces the clamp 5 forward with reaction at 8 to tighten the assembly on the stern of the canoe. Arm 29 in conjunction with the eccentrically bored boss 31 may be termed a shifter.

The spacer block 2 has a recess or socket 39 at its top, covered by mounting a plate 41 held by screws 43 on the top surface of clamp 5.

A rudder bracket 45 is quick-detachably mounted on the clamp 5 by means of a pivot comprising a pintle bolt or pivot pin 47 and a spring 49 coiled thereon. A tongue 51 of spring 49 reacts against clamp 5 to bias the pintle 47 and spring 49 to the rear of the recess 39. This is because the top surface of clamp 5 is inclined upwardly and the reaction of spring tongue 51 against it resolves into rearward and upward components of force on pintle 47. Spring 49 has its ends fitted into slots 44 of the bracket 45 and

biases bracket 45 to a vertical position. Bracket 45 is roughly channel-shaped in cross section (Fig. 4), having the channel opening facing forward and adapted to fit over the aft portion of clamp 5. The bracket 45 may be removed by swinging it up as shown by dotted lines at the left of Fig. 2, and then pushing it forward out of the slot 39, taking with it the spring 48. It may be reapplied by inverse movement. A pulley 46, by means of pins 48, is mounted in a horizontal plane on each side of bracket 45. Cable guides 50 are affixed to the sides of bracket 45 and serve to retain a control cable 52 in contact with pulleys 46. Two abutments or shoulders 53 are carried on the aft surface of bracket 45. These shoulders form a vertical socket for a rudder post bearing 55 and serve to maintain it in a substantially vertical position by their detent action.

Rudder bearing 55 is affixed to the rudder support by means of a bolt 57 the shank of which projects through the bracket 45. The head of bolt or pivot pin 57 is engaged by the bearing 55 and a spring 58 serves to bias the head of bolt 57 toward bracket 45. Clamp 5 has a large aperture 60 in block 2 to receive the shank of bolt 57, spring 58 and a nut 62 secured by a cotter pin. The rudder post bearing 55 includes a rudder post 59 having a rudder 61 adjustably mounted thereon by means of a bolt 63, a sleeve 65, a bushing 67 and an outer sleeve or collar 69. Rudder post 59 has a series of tapped holes 71, any one of which may be aligned with an aperture 73 of sleeve 65 to receive bolt 63. Sleeve 65 carries a crank disc 75 affixed to its upper surface. A crank pin 79 is affixed to the top surface of disc 75 by means of a screw or rivet 77. This crank pin 79 is cup-shaped and has two diametrically opposite openings 81 adapted to receive a knotted central portion of the control cable 52. Bushing 67 has a keyhole aperture 83 in its forward surface, and diametrically opposite the constricted portion of this keyhole aperture 83 there is a bushing opening or aperture 85. Collar 69 has an aperture 87 in its forward surface and a larger aperture 89 diametrically opposite therefrom. Sleeve 65 is free to slide upward in bushing 67 in the event the rudder, while in a straight downward motion, strikes some obstruction.

The forward portion of the steering device 3 of the present invention includes a port control member 91 and starboard control member 93. One end of control cable 52 is detachably connected to member 91 and the other end to member 93. The description of one control member will be sufficient. Control member 91 is quick-detachably mounted on the underside of a thwart 95 adjacent the port gunwale of boat 7. Member 91 comprises a hinge plate 97 which is affixed to the thwart 95 by means of screws 99, a hinge member 101, a hinge pintle 103 and a pedal 105. Hinge member 101 is affixed to pedal 105 by screws 107. Hinge member 101 carries two hooks 109 adapted to engage the pintle 103. The pedal 105 depends from thwart 95 and is adapted to be connected to the looped end of cable 52 by means of a pin 109 carried on the outer edge of pedal 105. Control member 93 is identical in construction to that of member 91, except that the pin corresponding to pin 109 is on the starboard side of the control member 93.

Referring now to Fig. 8, there is shown the stern clamp 5 affixed to the stern of canoe 1 by means of two bolts 111, springs 113 and wing nuts 115.

Operation is as follows:

The stern clamp 5 (Fig. 3) is assembled by organizing side plates 13, laminae 9 and sheets 11. They are held together by bolt 17 and nuts 19. The assembled clamp 5 is then fitted against the stern of canoe 1 so that one pliable sheet 11 is against each side of canoe 1. To make the inner surfaces of sheets 11 take the exact stern contours of canoe 1, the layer 15, of hardenable plastic material such as thinned plastic wood, is interposed between laminae 9 and sheets 11. By forcing clamp 5 against the canoe after the introduction of layer 15, sheets 11 will then be shaped as desired. The edges of sheets 11 are trimmed to match side plate 13 and any canvas or plastic which may have gotten into jaw apertures 25 or holes 27 is removed.

Clamp 5 is then held against the stern of canoe 1 so that aperture 21 may be viewed through jaw apertures 25. Bolt 7 is then inserted through the eccentrically bored boss aperture 32 of one of the arms 29 and through the strip aperture 21. Alignment is easily accomplished as the diameter of jaw aperture 25 is considerably larger than that of the shank of bolt 7. The other arm 29 is then engaged on bolt 7. By moving the outer ends of arms 29, the clamp 5 may be moved forward and upward to fit snugly the stern contours of canoe 1. When bolt 7 is thus properly aligned, locking bolt 35 is inserted through the arm apertures 33 and one of the locking apertures 35 and held firm therein by nut 36.

In some canoes, such as those of canvas construction, it may be desired to mount stern clamp 5 to the canoe 1 by using the two bolts 111, as shown in Fig. 8. In the latter instance, the arms 29 may be dispensed with. In either case, however, the shaping of the forward surfaces of clamp 5 to match the stern contours of canoe 1 is advisable and easily accomplished as described above.

The rubber bearing 55 is assembled by sliding bushing 67 into collar 69 until apertures 89 and 85 are matched. Bolt 57 is then inserted through these apertures, the constricted portion of keyhole aperture 83, the other collar aperture 87 and bracket 45. Bushing 67 is slid downward in collar 69 until the head of bolt 57 is engaged in the large end of the keyhole aperture 83 (as shown in Fig. 7). The spring 58 is compressed by nut 62 until the desired amount of pressure is exerted against collar 69.

Sleeve 65 is then inserted into the interior of bushing 67 until crank disc 75 is flush with the upper surfaces of collar 69 and bushing 67. The assembly of rudder bearing 55 is completed by sliding the rudder post 59 into the lower end of the sleeve 65 and then inserting bolt 63 through aperture 73 so as to engage the desired aperture 71.

The rudder bearing 55 is thus affixed to bracket 45 and may be pivoted about bolt 57. The bearing 55 is held in aligned position with bracket 45 by the combined action of abutments 53 and spring 58. The abutments in effect form a socket between them into which the bearing 55 is biased by means of spring 58. It is to be noted that the bearing surfaces between bushing 67 and sleeve 65 substantially prevent the entry of water and abrasive particles, as aperture 85 is covered by collar 69 (Fig. 7) when the rudder bearing 55 is in an assembled condition.

The rudder bracket 45 with rudder bearing 55 mounted thereon may be easily coupled to the clamp 5 by holding bracket 45 in the dotted-line position of Fig. 2, forcing spring tongue 51 up-

ward and then engaging pintle 47 and spring 49 in recess 39. The reaction of tongue 51 against clamp 5 biases spring 49 and pintle 47 to the rear of slot 39 and this same reaction serves to bias the rudder bracket 45 in the substantially vertical solid-line position of Fig. 2. Bracket 45 is then swingable about the axis of pintle 47. To uncouple bracket 45 from clamp 5, bracket 45 is swung upward into the dotted-line position of Fig. 2 and pushed forward.

The control cable 52 is then threaded through the openings 81 of crank pin 79 and the central portion knotted so as to fix it in the crank pin 79. Each end of cable 52 is passed between one guard 50 and its associated pulley 46. The looped extremities of cable 52 are then ready to be attached to the pins 109 of the control members 91 and 93.

Each pedal 105 is coupled to its hinge plate 99 by holding the pedal in the dotted-line position A of Fig. 2 and engaging hooks 109 with pintle 103. The pedal may then be swung downward into the solid-line position of Fig. 6 and the extremity of cable 52 looped over pin 109. The dotted-line position B of Fig. 2 is one exemplary operating position of the pedal when actuated by the operator's foot. The pedal may be conveniently disengaged by detaching the looped end of cable 52 from pin 109 and rotating the pedal into position A. The pedal is then pushed downward until hooks 109 are disengaged from pintle 103. No hand tools are needed to disassemble bracket 45 from clamp 5 or cable 52 and control members 91 and 93 from canoe 1.

When the steering device of the present invention is assembled and coupled to the stern of a craft which is water borne, the action of this rudder device is as follows:

The canoe 1 while floating free will not be affected in any manner by the operation of the steering device 3 if the control members 91 and 93 are undisturbed. If there is relative motion between the water and the canoe, rudder 61 is free to swing continuously and thus streamline itself with the water current. This is because the throw of crank pin 79 is less than the limits of throw of the pedals 105. Thus, if the forward motion of the water is greater than that of the canoe 1, the normally trailing edge of rudder 61 will align itself with the current so as to be forward of the rudder shaft 59.

If desired to direct the canoe 1 to a port heading, control 93 is actuated so that its pedal 105 is pushed forward to its extreme limit (position B, Fig. 6) and control member 91 is not actuated. This action causes the starboard portion of cable 52 to be tensioned and crank pin 79 to be held in a fixed position nearest to the starboard pulley 46. By actuation of control member 91 only, rudder 61 may be positioned approximately 45° to the longitudinal axis of the canoe so as to direct the canoe to a starboard heading. These two alternate predetermined positions of rudder 61 are determined by the diameter of the crank disc 75, the position of crank pin 79 thereon, and the position of the pulleys 46 relative thereto. Rudder 61 may be positioned to any desired intermediate steering position by cooperative pressure on control members 91 and 93. The relative pressure applied to each pedal 105 will determine the actual intermediate position of rudder 61.

The rudder bearing assembly 55, together with the rudder bracket 45, is swingable on the axis of pintle 47 and spring 49, and will swing up when floating or underwater obstruction or

debris is encountered by rudder 61 or shaft 59. As spring 49 serves to bias the rudder shaft 59 down into a substantially vertical position, the shaft 59 will return to this position after the obstruction has been passed over. The spring-biased hinging action of bracket 45 on clamp 5 protects all elements of the device 3 from damage. Undue stress is not placed on the canoe 1.

Quite frequently when negotiating a curve in a river the rudder may be struck laterally by some floating object. In this case the pivotal action of bearing 55 about bolt 57 serves to protect the device 3 and canoe 1 from damage. The dotted-line position of bearing 55 in Fig. 3 illustrates this pivotal action. The amount of force required to cause bearing 55 to be disengaged from between shoulders 53 is dependent upon the compression of spring 58 and the relative dimensions of collar 69 and shoulders 53. In the solid-line position of parts in Fig. 3, the sleeve 85 nests between members 53 (as shown in Fig. 4). In the dotted-line position in Fig. 3, sleeve 85 rides upon members 53 but readily biases back into nesting position after the instigating obstruction has been passed. The compression of spring 58 is conveniently adjustable by nut 62. Thus, combined hinging action about pintle 47 and pivoting action about bolt 57 may occur if the impact of the obstacle against rudder 61 is at an angle to the direction of movement of the boat. This combined hinging action, together with the free rotation of shaft 59 and the sliding action of sleeve 65 in bushing 67, renders possible universal movement of rudder 61.

It is to be understood that clamp 5 will also serve as an excellent outboard motor mounting. This is one advantage of the quick-detachable character of the rudder post assembly. In such a use, clamp 5 is most conveniently mounted by means of the alignable bolt 7, which may be so moved by arms 29 as to insure a snug fit between the jaws of clamp 5 and the stern of canoe 1.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A rudder construction for a boat comprising a stern bracket, a rudder bracket having a pivotal connection with the stern bracket with the axis of said pivotal connection extending horizontally and transverse to the longitudinal axis of the boat so that the rudder bracket may swing in the longitudinal vertical plane of the boat.
2. A rudder construction for a boat comprising a stern bracket, a rudder bracket having a pivotal connection with the stern bracket with the axis of said pivotal connection extending horizontally and transverse to the longitudinal axis of the boat so that the rudder bracket may swing in the longitudinal vertical plane of the boat, a rudder bearing having a pivotal connection with the rudder bracket with the axis of this pivotal connection transverse to the axis of said bearing, said pivotal connection being a slidable connection allowing for bodily movement of the rudder bearing toward and away from the rudder bracket, means biasing the rudder bearing toward and against the rudder bracket, and detent means on the rudder bracket engaged by the rudder bearing when against the bracket for maintaining the rudder bearing in a vertical position.
3. A universal movement rudder construction

for a boat comprising a stern attachment having a horizontally and forwardly directed recess transverse to the longitudinal axis of the boat, a rudder bracket having a pivot pin removably received in the recess, a spring carried by the pivot pin and acting against the stern attachment to bias the pin against the rearward end of the forwardly directed recess and to bias the rudder bracket to swing downward to a generally vertical position determined by engagement of the bracket with the stern attachment, a rudder bearing carried by said rudder bracket, said bearing being located with its axis transverse to said pivot pin, and spring detent means between said rudder bearing and said rudder bracket normally holding the rudder bearing against said bracket in a vertical position but which permits lateral rotation of the bearing around a longitudinal axis of the boat in response to lateral forces on a rudder supported therein.

3. A universal movement rudder construction for a boat comprising a stern attachment having a horizontal and forwardly directed recess transverse to the longitudinal axis of the boat, a rudder bracket having a pivot pin removably received in the recess, a spring coiled around the pivot pin and having a tongue acting against the stern attachment in such direction as to bias the pin against the rearward end of the forwardly directed recess and to bias the rudder bracket to swing downward to a generally vertical position determined by engagement of the bracket with the stern attachment.

4. In a steering device for boats, a rudder bracket having an opening, a pivot pin slideable in the opening in the bracket, a rudder bearing carried by the pin with the axis of the bearing transverse to the pin, a rudder post rotary in the bearing, a rudder fixed to the post, a spring reacting from the bracket against the pin to bias the bearing toward engagement with said bracket, and a detent means on the bracket engageable by the sides of the bearing when the latter is drawn by the spring against the bracket determining a vertical position of the bearing, the bearing being swingable about the axis of the pivot pin by withdrawal away from the bracket.

5. In a waterproof boat rudder construction, a rudder bracket having an opening, a sleeve having a bolt opening in one side and an aligned access opening in its opposite side, a bolt having a head within the sleeve and having a shank extending through the bolt opening and the opening in the rudder bracket, a bushing slideable in said sleeve and having a first opening in one side which is axially aligned with but displaced from said access opening in a normal position of the bushing, the bushing also having a second opening of keyhole shape and thereby including a head opening and a slot extending axially of the bushing from the head opening, said head opening receiving the head of the bolt when the bushing is in normal position, said bushing being slideable in the sleeve to an access position in which the first opening in the bushing is aligned with said access opening in the sleeve upon withdrawal of the head of the bolt from within said head opening, the shank of the bolt then being received in the slot of the keyhole opening.

6. Steering means for a canoe comprising a

stern bracket having a vertical notch receiving the stern of the canoe, said canoe having a transverse horizontal opening in the stern and said bracket having side openings aligned with the opening in the stern of the canoe, a pintle extending loosely through said opening for attaching the bracket to the canoe, said pintle being sufficiently loose in said canoe opening as to permit shifting of the position of the bracket relative to the canoe, adjustable rotary eccentric means supporting the pintle, means for anchoring said eccentric means in various positions of adjustment, a rudder bearing affixed to said rudder bracket, and a rudder post rotary in said bearing for steering movement.

7. In a rudder construction having a stern bracket for attachment to the stern of a boat, a rudder bracket pivoted on the stern bracket for swinging movement about a horizontal axis transverse to the longitudinal axis of the boat, a rudder bearing pivoted on the rudder bracket for rotary movement about an axis transverse to the axis of the bearing and extending longitudinally of the boat, a rudder post rotary in the bearing, and a rudder on the post mounted for steering movement.

8. A steering mechanism for boats comprising a stern clamp fastened to the boat, a bracket hingedly mounted on said clamp and swingable in a vertical longitudinal plane relative to the boat, at least two abutments carried on the aft surface of said bracket, a rudder post bearing pivotally mounted on said bracket between said abutments and rotatable about a longitudinal axis of the boat, a rudder post carried by said bracket having a rudder affixed thereto, a pintle having a spring coiled thereon and mounted on said bracket, a horizontal and forwardly directed recess in said clamp to receive said pintle and spring, and a tongue on said spring reacting against the clamp to bias the bracket to said clamp in a substantially vertical coupled position and to bias the rudder post in a vertical position against movement in a vertical longitudinal plane of the boat.
